UNITED STATES PATENT OFFICE

91,124

DESIGN FOR A STOCKING

John William Smith, Schillington, Pa., assignor to Holeproof Hosiery Co., Milwaukee, Wis.

Application March 20, 1933. Serial No. 47,529

Term of patent 3½ years

To all whom it may concern:

Be it known that I, JOHN WILLIAM SMITH, a citizen of the United States, residing at Shillington, in the county of Berks and State of Pennsylvania, have invented a new, original, and ornamental Design for Stockings, of which the following is a specification, reference being had to the accompanying drawing, forming part thereof.

I claim:

The ornamental design for a stocking, as shown and described.

In testimony whereof, I affix my signature at Shillington, Pennsylvania.

JOHN WILLIAM SMITH.
